UNITED STATES PATENT OFFICE

JOSEPH S. HIGBIE, OF ROCKVILLE CENTER, NEW YORK

CONVERTIBLE GAS RANGE

Application filed June 6, 1929. Serial No. 368,930.

This invention relates to certain improvements in convertible gas ranges, and the nature and objects of the invention will be readily recognized and understood by those skilled in the arts involved in the light of the following explanation and detailed description of the accompanying drawings illustrating what I at present consider to be the preferred embodiments or mechanical expressions of my invention from among various other forms, arrangements, combinations and constructions of which the invention is capable within the spirit and scope thereof.

Gas ranges or stoves, and particularly those of the domestic types, perform no useful function or purpose in a kitchen when not in use for cooking purposes. This is especially disadvantageous in the smaller kitchens, such as the so-called kitchenettes and apartment kitchens, because a range or stove, except for periods when it is being used for cooking, merely occupies space to the exclusion of other highly useful and desirable articles of kitchen furniture, such for example as kitchen tables and cabinets. Further, as the smaller kitchens necessitate a relatively small range or stove to occupy a minimum of space, it frequently happens that such relatively small ranges do not provide sufficient types of ovens or a sufficient number of burners to meet the demands of cooking, with the resultant difficulties in properly and efficiently carrying out the desired range of cooking operations with them.

The present invention holds as one of its main objects the provision of a gas range or stove which will overcome the foregoing difficulties, through a design, construction and arrangement by which the range or stove is rendered quickly convertible to provide a table or cabinet having a top table forming surface; which when so converted presents the appearance of a table or cabinet and not of a range or stove; which is attractive and pleasing to the eye; and which is so constructed that necessary and essential range or stove elements thereof are utilized to convert the range into the desired table and change its appearance from that of a stove, thus eliminating added elements and structural complexi-

ty in the stove, in order to secure the results desired.

A further object of the invention is to provide a design, construction and arrangement of gas range or stove, through the medium of which a relatively small and very compact range is possible, yet which permits of the provision of sufficient burners and the several types of ovens necessary, for efficiently carrying out and performing the usual range of domestic cooking operations in an efficient manner; and further to provide a construction which enables all gas pipes, controlling devices, hinges and the like, as well as securing elements such as bolts, screws or rivets, being mounted and disposed on the interior or at the back of the range, hidden from normal view with the range in installed position.

Another object of the invention is the provision of an improved arrangement and mounting of the oven burners in a gas range or stove, and in the arrangement of the gas supply pipes thereto and the air mixing device therefor.

A further object of the invention is the provision of a gas range or stove structure having units or sections which can be readily removably mounted supported on and extending upwardly from the back of the stove to provide cabinet and shelf space in accordance with the desires or needs of the user or the requirements of a particular installation, and which units or sections are further capable of forming several different combinations with the range.

Another object of the invention is to provide a construction of gas range or stove for carrying out the foregoing objects and securing the desired results, which will be mechanically simple, readily manufactured at relatively small cost; which can be readily installed at small cost and occupy a minimum of space; which will require a minimum of care and cost of maintenance after installation; and which will meet the building and safety requirements for such types of ranges or stoves.

With the foregoing general objects, as well as certain other objects and results in view which will be readily recognized from the

following explanation, the invention consists in certain novel features in construction and in combinations and arrangements of parts and elements, as will be more fully and particularly referred to and specified herein-after.

Referring to the accompanying drawings in which similar reference characters refer to corresponding parts throughout the several figures:

Fig. 1, is a view in front elevation of a gas range or stove embodying features of the invention, and with the several converting elements thereof in position to permit of use of the range or stove for cooking.

Fig. 2, is a view in top plan of the stove of Fig. 1, showing the arrangement of cooking top burners and gas supply pipes.

Fig. 3, is a vertical transverse sectional view taken on the line 3—3, of Fig. 1.

Fig. 4, is a top plan view of the range of Fig. 1, converted to form a table.

Fig. 5, is a view in end or side elevation of the converted range of Fig. 4.

Fig. 6, is a view of the range of Figs. 4 and 5, as converted to provide, and present the appearance of, a table and cabinet.

Fig. 7, is a view of the upper end or cooking top portion of the range of Fig. 1, with the detachable splasher and plate shelf in mounted position thereon, and the range open for cooking.

Fig. 8, is a view similar to Fig. 7, but with the range converted to form and provide the table and cabinet.

Fig. 9, is a view in front elevation of the range of Fig. 7.

Fig. 10, is a vertical transverse section through the range of Fig. 1, taken on the line 10—10, through the broiler oven of the range, and showing the mounting and arrangement of the burner in the broiler oven.

Fig. 11, is a detail horizontal section through a portion of the range to show the wall construction and arrangement thereof by which the fastening elements thereof are hidden from view at the front of the range.

Fig. 12, is a detail vertical sectional view through a portion of the range walls at the bottom or lower end thereof.

Fig. 13, is a front elevation of the range showing a cabinet unit in position mounted thereon, the range being shown in converted form.

Fig. 14, is a view in end elevation of the cabinet unit in mounted position.

Fig. 15, is a vertical transverse section through the cabinet unit and upper part of the range on which mounted, the range being shown in open unconverted form.

One type and arrangement of gas range or stove in which the several features of the invention are incorporated is disclosed herein-with purely by way of example and not of limitation, for the purpose of explaining the

principles and several features of the invention so that those skilled in the art may understand the same by reference hereto. However, the invention is not limited or restricted to the herein presented and illustrated type and arrangement of gas range, or to the number of cooking top burners and the particular arrangement thereof, or to the number of ovens or the character of cooking such ovens are designed to carry out, but the several features of the invention are of general adaptation to various other types and arrangements of gas ranges, and the invention contemplates and includes such other adaptations and the mechanical forms and arrangements which they may happen to take.

In the example here shown, referring now to Figs. 1 to 3 of the accompanying drawings in particular, a gas range embodying the several features of the invention is illustrated, of the relatively small kitchen type, having a cooking top at the upper end of the stove with, in this instance four burners B, and with the body of the stove or range designed, arranged and constructed to provide two ovens, a baking oven 1 and a broiling oven 2 side by side; and further to provide a drawer 3 below these ovens. The body of the range or stove, referring here to Figs. 11 and 12, is constructed of suitable frames to which are secured sheet metal walls, the arrangement and construction being such that all securing elements, door hinges and the like, are hidden from view when looking at the front of the range.

For example, a range frame 4 (see Figs. 3 and 12) of L-section provides the bottom frame to the four corners of which the stove supporting legs 5 are bolted or otherwise suitably secured. The opposite side or end walls 6 and the rear or back wall 7 are formed with inturned horizontal flanges 8 (see Figs. 3 and 12) which are bolted to the outturned horizontal flanges of the bottom frame 4, and the end walls 6 are formed with the flanges 6^a at their rear edges which are fitted over and bolted, riveted or otherwise secured to the back wall 7, as will be clear by reference to Fig. 11 of the drawings. The front edges of the side walls 6 are formed with the in-turned flanges 6^b and an L member or angle bar 9 is secured in vertical position to and along each of these end wall flanges 6^b, respectively, as by spot welding the same thereto. A top wall or sheet 10 is suitably secured to the upper ends of side walls 6 and back wall 7, over and closing the upper end or top of the range body.

Spaced a distance upwardly from the bottom frame 4, a horizontal wall 11 (see Figs. 3 and 10) is secured across and between the side walls 6 and back wall 7 to form the bottom wall of the ovens 1 and 2, and vertical wall 12 (see Fig. 3) is suitably secured between the top and bottom walls 10 and 11, inter-

mediate end walls 6, to divide and form the space therebetween into the ovens 1 and 2. A horizontal front panel 14 is secured across and between side walls 6 along and over the forward edge of and extending upwardly a distance from, the bottom wall 11 of the ovens, and a vertical panel 15 is secured over and along the forward edge of the oven division wall 12, extending upwardly from panel 14 to the top sheet or wall 10. In this manner front openings are formed to the ovens 1 and 2, and in these openings suitable oven doors 16 are swingably mounted at their lower edges by concealed hinges 17 secured on the inner sides of the doors and to the horizontal panel structure and frame 14. The oven doors 16 are thus swingable outwardly on hinges 17 to position opening the ovens 1 and 2, and swingable upwardly to the closed positions shown in the drawings. When in closed position due to the mounting and arrangement, these door hinges 17 are concealed from view at the front of the stove or range. The drawer 3 is slidably mounted and confined in the space between the bottom frame 4 and the oven bottom wall 11, supported on bottom frame 4. The front of the drawer with the latter in closed position occupies and fills the space between the side walls 6, and the bottom frame 4 and front panel 14, so that with the oven doors 16 closed, the range presents a closed front, unbroken and unmarred by hinges, securing elements and the like, and giving the appearance of an article of furniture such as a cabinet without the unsightly appearance of the usual gas stove or range.

The cooking top space within which the burners B are disposed above the range top sheet or wall 10, is provided by the side walls 6' and back wall 7' extending upwardly from top sheet 10 in substantial continuation of the side walls 6 and back wall 7, respectively. The upper ends of these cooking top walls 6' and 7' are provided with inturned horizontal flanges, and the forward edges of the side walls 6' are also formed with the inturned vertical flanges 6^a which are cut away at their lower portions above the top plate 10 to form the slots 6^a for a purpose appearing hereinafter. The walls 6' terminate at their forward or front ends which are formed by the flanges 6^a, spaced equal distances inwardly from the front side of the range body, so as to provide an unobstructed horizontal ledge or shoulder across the top plate or wall 10 on the upper side and along and adjacent the forward edge thereof, as will be clear from Figs. 2 and 3 of the drawings.

A rectangular burner grid or grate receiving and supporting frame 20, formed in the present example of L shape in cross section with one flange thereof disposed horizontally and extending inwardly therearound, is

mounted and secured in position around the inner side edges of the cooking top side walls 6' and back wall 7', with the vertically disposed flange of said frame extending upwardly from the inner sides of the top edges of such walls, a distance thereabove. The width of the grate supporting frame 20 is less than the length of the side walls 6', and the forward bar or side of this frame extends across and between the side walls 6', but spaced a distance inwardly from their forward ends and above the top plate or wall 10. The inwardly extending and horizontally disposed flange of the frame 20 provides a shoulder therearound for receiving and supporting any suitable or desired burner grate 21.

A gas supply manifold M, not only for the cooking top burners B, but also for the oven burners to be hereinafter described, is mounted in the space above the top plate 10 between the front edge thereof and the grate frame 20, and this manifold is supported at its opposite ends adjacent side walls 6', by the supporting brackets 21 secured to and extending forwardly and downwardly from the grate frame 20. (See Figs. 2 and 3.) A gas supply pipe P is coupled to one end of manifold M for supplying gas thereto, and this supply pipe extends rearwardly across the top wall 10 adjacent the inner side of a side wall 6', to the rear of the range or stove where it projects a distance in position for connection with the gas supply line of a kitchen in which the stove is to be installed. The supply pipe P as well as the manifold M are thus both disposed and mounted within the confines of the range structure and do not project at the front or sides thereof.

The burners B, of the instant example are four in number, and are disposed spaced apart below the grate supporting frame 20. Each burner B is supplied with gas from the manifold M by a gas pipe b, which pipe b also supports the burner, and a handled valve or cock C is mounted in the supply pipe b to each burner for controlling the supply of gas thereto. In this manner the manifold M and the burner valve C are spaced inwardly a distance from the front of the burner but readily accessible.

The oven 1 is of the baking type and is provided with a burner 22, referring now to Fig. 3 of the drawings, mounted at the lower side of the oven above the bottom wall 11, and this burner 22 is of a type in which the burner nozzles or gas discharge orifices are on the under side of the burner. Any suitable or desired baffle plate or wall 23 is mounted across the oven above the burner 22 for a purpose well understood in the art. Now according to a feature of the invention, the burner 22 of oven 1, is supplied with gas from the manifold M, and this is accomplished by means of a gas supply pipe 24 which extends from an intermediate point on

the manifold, rearwardly across top plate 10 between the inner pair of burners B, and then downwardly on the exterior of the range back wall 7 and inwardly to burner 22, any suitable control valve C' being mounted in pipe 24 adjacent and accessible at manifold M. By so mounting and arranging the pipe 24, it is hidden from view at the back of the range, while the oven burner 22 can be operated and controlled from the front of the range at manifold M.

The oven 2 is a broiling oven and is supplied with a broiler burner 25, referring now to Fig. 10 of the drawings. The burner 25 is mounted in the upper end of oven 2 and is supplied with gas from manifold M by a pipe 26 similar to pipe 24 in its arrangement and mounting, that is, pipe 26 extends across top wall 10, then downwardly on the exterior of the back wall 7 to the burner 25. A suitable valve C' is mounted in the pipe 26 adjacent manifold M for controlling the burner 25, as will be readily understood.

Preferably the ovens 1 and 2 are provided with suitable flues F in communication with the upper ends thereof through the range back wall 7. These flues are terminated at their upper ends so as not to extend upwardly above the range and may have the usual mineral wool placed in their upper ends if desired.

Another feature of the invention resides in the arrangement of air mixing devices for the oven burners 22 and 25, and in the provision for ready adjustment of these devices. The supply pipes 24 and 26 enter the ovens 1 and 2 through the back wall 7 adjacent and on opposite sides of the oven division or partition wall 12, and an air mixing device D, referring now to Figs. 3 and 10 of the drawings, is mounted in each pipe 24 and 26, respectively, adjacent the burners 22 and 25. The mixing devices D are similar and each comprises a mixing chamber in the supply pipe in which same is connected, and a depending air supply tube D' having a valve V at its lower air intake end for adjusting and controlling the air supply to the mixing chamber. In the example hereof, the air tubes D' of the mixing devices D in pipes 24 and 26, depend downwardly to and extend through the bottom wall 11 with the valves V disposed below this wall in the space above drawer 3. The ovens 1 and 2 are preferably provided with the usual inner linings or walls (not shown) spaced from the walls of the range, and the air tubes D' are disposed at opposite sides of oven division wall 12 between such linings and the wall 12. By adjusting valves V the proper combustible mixture for burners 22 and 25 can be maintained, the valves V being accessible from the front of the range through the drawer space, and the mixing devices D are thus positioned out of sight on the interior 35 of the stove or range.

The invention provides, as a fundamental feature and characteristic thereof, for the conversion of a gas range or stove into a useful article of kitchen furniture, such as a table and cabinet, which will present when converted a pleasing appearance. In carrying out this feature with the gas range or stove described hereinbefore, the invention utilizes certain elements of the range or stove. The range of the example is provided with a drip pan 30 slidably mounted and supported for ready withdrawal on the top plate or wall 10 of the range beneath the cooking top with its burners B and manifold M, as clearly shown by Figs. 1, 2 and 3. This drip pan 30 is formed with a depending flange 31 therearound upon which it rests and is supported in position beneath the cooking top, and is slid to and from position through the slots or cut away portions 83 in the flanges 6° of cooking top side walls 6'. 70 75 80 85

The range or stove is also provided with a removable back rail 40 which is mounted on the upper edge of the back wall 7' of the cooking top and which extends thereacross and upwardly therefrom and bearing against the adjacent flange of grate frame 20 which maintains this rail in position against lateral displacement. Back rail 40 90 is removably secured in position on wall 7' by a pin 41 secured to the rear side of the back rail intermediate its ends and depending a distance downwardly therefrom, which pin fits down into and is received in a socket 100 member 42 fixed in vertical position adjacent the upper edge of rear wall 7'. 95

When the range or stove is not in use for cooking and it is desired to convert the same into a table and cabinet with the appearance of a stove masked, the drip pan 30 is withdrawn from beneath the cooking top, and the back rail 40 is lifted from position on the wall 7'. The back rail 40 is then placed in position across and extending between the forward ends of cooking top side walls 6', and supported on the range top wall 10 along the forward edge thereof, the pin 41 being received and fitted in a bore or hole 43 (see Fig. 2) formed through wall 115 10. In this position the back rail 40 forms a cover or closure for the manifold M, as will be clear by reference to Figs. 5 and 6 of the drawings, and is held in position against displacement by pin 41 and the ends 110 of the rail bearing against front end flanges 6° of the cooking top side walls 6'. 115 120 125

The drip pan 30 is then placed in position over and completely covering the cooking top and forming a table top for the range, as shown by Fig. 4 of the drawings in particular, and thus completing the masking of the range and its conversion into a table and cabinet, with the appearance of an article of kitchen furniture. The drip 130 135

pan 30 with its depending flange 31, is so constructed and arranged as to cooperate with and fit over the grate frame 20 of the cooking top with flange 31 fitting around the vertical flange of frame 20 and resting upon the upper edges of walls 6' and 7', and with the flange 31 at the forward side of the drip pan resting upon the upper edge of manifold cover forming back rail 40, which latter forms a support therefor. The drip pan 30 is preferably formed with a readily washable surface, such as an enameled surface, and provides an efficient table top forming surface.

15 In converted form the gas range loses its appearance as such and presents the appearance of and does provide a useful article of kitchen furniture, thus reclaiming the loss of space resulting with a range or stove during 20 periods when not in use for cooking. The entire cooking top of the range is covered by the table top forming drip pan 30, while the entire manifold and valve assembly is also covered and closed from view by the manifold cover forming back rail 40, these elements (back rail and drip pan) meeting and joining at the front of the range. The range can be quickly prepared for cooking operations by merely lifting the drip pan 30 and 25 back rail 40 from their range converting and closing or masking positions and returning them to their respective positions as elements of the range.

Where it is desired to use a higher or taller back splasher than the back rail 40 and to secure a plate shelf, the invention provides a back splasher and plate rail unit or section 30 for detachable mounting on the top of the range along the rear thereof, as shown by 35 Figs. 7, 8 and 9 of the drawings to which particular reference is now had. This unit 50 comprises the side walls 51 decreasing in width downwardly toward the rear thereof and having the top plate shelf 52. The forward edges of side walls 51 are formed with the inturned flanges 51^a which terminate spaced from the bottom edges of these walls, and the unit is detachably mounted on the upper end of the range by the bolts 53 or 40 the like extended through the lower ends of walls 51 and the cooking top side walls 6' overlapped thereby, the lower ends of the inturned flanges 51^a supported and resting upon the upper edges of side walls 6'. On 45 the exterior of the rear side or back of unit 50 adjacent the upper end thereof, a socket member 42 is secured for receiving the back rail pin 41 to enable mounting back rail 40 at the upper end of the unit 50 along the shelf 52 thereof, as shown by Figs. 7 and 9. The operation of the range converting drip pan 30 and back rail 40 to convert the range into a table and cabinet is the same as previously described, and is illustrated by 50 Fig. 8.

The invention also further provides another unit or section for detachable mounting on and addition to the upper end of the splasher and plate shelf unit 50, and such a unit or section 60, is illustrated in Figs. 13, 70 14 and 15 of the accompanying drawings. This unit 60 comprises and forms a cabinet having front doors 61, and is constructed and arranged so that its side walls 62 fit down over the opposite side walls 51 of unit 50, to which they are detachably secured by bolts, screws or the like 63. The cabinet unit 60 can thus be detachably mounted on the upper end of unit 50 and thereby increase the usefulness of the range where desired. With the cabinet section 60 the operation of the range converting elements 40 and 30 remains the same, with the exception that back rail 40 when removed from position as a manifold cover, is merely placed or 75 laid on top of the cabinet section 60.

15 In the design, arrangement and construction of gas range or stove embodying the several features of the invention, thus enables the production of a range having the necessary 80 ovens and cooking top burners for a wide range of cooking operations, while retaining simplicity of structure, compactness and relatively small size, with efficiency in operation, ease of installation, and low maintenance costs. The convertible features enable 85 not only the utilization of the range for practical purposes during non-cooking periods, but the formation of a useful article of furniture of pleasing appearance, and all 90 without the employment of other than elements of the cooking range or stove.

95 It is also evident that various changes, modifications, variations, additions and substitutions might be resorted to without departing from the spirit and scope of my invention, and hence I do not desire to limit myself in all particulars to the exact and specific disclosures hereof.

100 Desiring to protect my invention in the broadest manner legally possible, what I claim is:

1. In a gas range, a cooking top including 105 gas burners and a gas supply manifold therefor at the forward side thereof, a drip pan removably mounted beneath said burners, a back rail removably mounted at the rear of the cooking top, said drip pan removable and adapted to be mounted over and across the cooking top and burners to 110 form a table top for the range, and means to attach said back rail in position mounted across the forward side of the cooking top to form a cover for the manifold.

115 2. In a gas range, a cooking top including 115 gas burners and a gas supply manifold therefor along the forward side thereof, the cooking top formed with a space beneath said burners and manifold, a drip pan removably mounted in the space beneath said 120

70

burners, a back rail removably mounted at the rear of the cooking top, said drip pan removable and formed to be mounted on the upper side of and fit over and cover the 5 cooking top to convert the same into a table top, said cooking top constructed to removably receive and support said drip pan in position thereover against displacement, said back rail adapted to be mounted in 10 vertically disposed position across the forward side of the cooking top to form a cover for the manifold and to receive and support the forward side of the drip pan in position on the cooking top, and the range and forward side of the cooking top constructed to removably receive and engage the back rail 15 to maintain the same in position against displacement.

3. In a gas range, a cooking top including 20 gas burners and a burner grate frame, said 25 grate frame having a vertical flange therearound, the cooking top formed with a space beneath said burners, and a drip pan removably mounted in the space beneath said cooking top burners and formed with a depending flange therearound supporting the pan in position, the said drip pan adapted to be placed over said cooking top and burners to 30 form a table top for the range, with the drip pan flange received over and fitting around said grate frame vertical flange to maintain the pan against displacement.

4. In a gas range, a cooking top including 35 opposite side walls and a back wall, gas 40 burners disposed within said cooking top walls, a burner grate frame mounted and supported on said walls, said frame having a vertical flange extending upwardly above the upper edges of said walls along the inner side edges thereof, and a drip pan removably mounted within said walls beneath said burners and formed with a depending flange therearound, the said drip pan adapted to 45 be placed over said cooking top and burners to form a table top for the gas range, with the drip pan flange resting upon the upper edges of the cooking top walls, and received over and fitted around said grate frame vertical flange.

5. In a gas range including a cooking top 50 and gas burners with a gas supply manifold mounted across and accessible at the forward side of said cooking top, a back rail removably mounted across and extending upwardly 55 from the rear of said cooking top, said back rail adapted to be mounted across the forward side of and closing the cooking top to form a cover for masking the manifold, the range at the forward side of the cooking 60 top constructed to removably receive and support said back rail in manifold cover forming position, and means for removably attaching said back rail in manifold cover position against displacement.

6. In a gas range, side by side ovens, a

cooking top above said ovens, including gas burners and a supply manifold across the forward side of said cooking top; a gas burner in each oven, and a gas supply pipe for each oven burner extending rearwardly 70 through the cooking top, downwardly on the exterior of the rear wall of the gas range, and then forwardly to its respective oven burner.

7. In a gas range, side by side ovens formed 75 therein having a division wall therebetween, a cooking top above said ovens and including a gas supply manifold disposed across the forward side thereof accessible from the front of the range, a gas burner in each oven, and gas supply pipes from said manifold at 80 points intermediate its ends to said oven burners, respectively, said supply pipes extending rearwardly through the cooking top, downwardly on the exterior of the rear of the range, and then inwardly at opposite sides 85 of the oven division wall but adjacent thereto, to the respective oven burners.

8. In a gas range, an oven formed therein, a burner in said oven, a gas supply pipe to 90 said burner, and an air mixing device in said gas supply pipe at a point within the oven, said device including an air supply tube depending therefrom through the oven to a point beneath the oven on the exterior thereof, and an adjustable valve in the lower end 95 of said tube for controlling flow of air to said mixing device.

9. The combination in a gas range having 100 a cooking top and a removable back rail mounted along and extending upwardly from the rear side thereof, of a detachable back 105 splasher and shelf unit for detachable mounting at the rear of the cooking top in place of said back rail, the said unit constructed at its upper side to removably receive the back rail in position thereon extending upwardly therefrom along the rear thereof.

10. The combination in a gas range having 110 a cooking top and a removable back rail mounted along and extending upwardly from the rear side thereof, of a detachable back 115 splasher and shelf unit for detachable mounting at the rear of the cooking top in place of said back rail, and a cabinet unit detachably mounted on the upper side of and supported by said splasher unit.

11. In a gas range, a cooking top including 120 gas burners and a gas supply manifold therefor along the forward side thereof, said cooking top having closed rear and end walls with the forward side normally open to expose the manifold, a drip pan removably mounted within the cooking top beneath said burners, said drip pan adapted to be removed 125 and mounted in position on the upper side of and covering the cooking top, said cooking top formed to removably receive and support said drip pan in position thereover against displacement, and a wall forming member 130

removably mounted across the forward open side of the cooking top to close the same and mask said manifold, said member receiving and providing a support for the forward edge 5 of the drip pan with said pan in position over the cooking top.

12. In a gas range, a cooking top, a manifold at the forward side of the cooking top, a drip pan removably mounted under the 10 cooking top and adapted to be removed and mounted in position on and over the cooking top to form a cover therefor, said cooking top formed to receive and support the drip pan in position thereover against displacement, 15 and a wall forming member removably mounted across and closing the forward side of the cooking top to conceal and cover said manifold, the forward side of the drip pan meeting with the upper side of said wall 20 forming member to complete the masking of the cooking top and manifold.

13. In a gas range, a cooking top including gas burners and a manifold across the forward side thereof, a drip pan removably 25 mounted over and covering said cooking top, a wall forming member removably mounted across and closing the forward side of the cooking top to conceal said manifold and complete with the drip pan the masking of 30 the cooking top, said wall forming member removable to open the forward side of the cooking top and expose the manifold, and the cooking top formed to receive the drip pan through the open forward side and 35 removably position the same below said burners, with the upper side of the cooking top opened to expose the burners.

14. In combination, a gas range having a cooking top including gas burners, and a drip 40 pan receiving and supporting space in the cooking top beneath said burners, the upper side of said cooking top constructed to removably seat and maintain a top forming cover in position across and covering the 45 same, and a combined drip pan and cooking top cover formed to removably fit into said cooking top space beneath said burners as a drip pan therefor, and to fit over and seat on the upper side of said cooking top to 50 provide a top forming cover therefor.

15.
